A. S. Vedder, of Troy, N.Y.
Assign to
Newberry, Filley & Co, of Troy, N.Y.
Letters Patent No. 865. Dated Jan 15th 1837.

The Schedule referred to in these Letters Patent and

making part of the same.

To all whom it may concern.

Be it known that A. N. S. Wedder, of the city of Troy, in the county of Rensselaer, and State of New York, has invented or produced a new and original design for Plate and Feet of an elevated oven Cooking Stove, called the "Wisconsin"; and I do hereby declare that the following is a full and exact description of the same, reference being had to the annexed drawings, making a part of this specification in which

Figure 1. is an elevation of the front plate with one of its doors.

Figure 2. of a side plate, with its doors.

Figure 3. of a side plate of the oven.

Figure 4. of an end plate of the oven, with its door, and.

Figure 5. of a foot.

The same letters refer to like parts in all the figures.

My design consists in ornamenting the panels A. B. C, and D, of the doors, and E, of the side plate of the oven, with the peculiarly formed shell like ornament composed of the swelling corrugated surface a, crimped band b, check-work ribs c, and intervening flutes d., all formed and arranged together as shown in the annexed drawings: also in ornamenting the feet with the shell e, leaf f, and check-work bars g, as represented in figure 5.

What I claim as my invention or production and desire to secure by letters patent, is,

Ornamenting the panels and feet of cooking stoves having elevated ovens, in the manner
